DESIGN FOR AN IRONER

William Earle Stilwell, Jr., Cincinnati, Ohio, assignor to Empire Ironer, Incorporated, Cincinnati, Ohio, a corporation of Ohio

Application March 17, 1938, Serial No. 75,900

Term of patent 14 years

To all whom it may concern:

Be it known that I, William Earle Stilwell, Jr., a citizen of the United States, residing at Cincinnati, in the county of Hamilton and State of Ohio, have invented a new, original, and ornamental Design for an Ironer, of which the following is a specification, reference being had to the accompanying drawing, forming a part thereof.

I claim:

The ornamental design for an ironer, substantially as shown.

WILLIAM EARLE STILWELL, JR.
